Primary Examiner — Austin Murphy*(74) Attorney, Agent, or Firm* — Nirav D. Parikh; Edgar A. Zarins(57) **CLAIM**

The ornamental design for a mat, as shown and described.

DESCRIPTION

FIG. 1 is a front perspective view of a mat in an open configuration in accordance with the present design;

FIG. 2 is a top plan view thereof;

FIG. 3 is a bottom plan view thereof;

FIG. 4 is a right side elevational view thereof;

FIG. 5 is a left side elevational thereof;

FIG. 6 is a front elevational view thereof;

FIG. 7 is a rear elevational view thereof; and

FIG. 8 is a perspective view of the mat in a half rolled configuration in accordance with the present design;

FIG. 9 is a perspective view of the mat in a fully rolled configuration in accordance with the present design;

FIG. 10 is a top plan view thereof;

FIG. 11 is a bottom plan view thereof;

FIG. 12 is a right side elevational view thereof;

FIG. 13 is a left side elevational thereof;

FIG. 14 is a front elevational view thereof;

FIG. 15 is a rear elevational view thereof; and,

FIG. 16 is a perspective view of the mat in an unrolled configuration in its environment.

The broken lines shown are not part of the claimed design and are only for purposes of showing environment.
